(57) **CLAIM**

The ornamental design for a portion of digital audio player,
as shown and described.

DESCRIPTION

FIG. 1 is a front, bottom and right side perspective view of
a portion of digital audio player, showing our new design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and,
FIG. 7 is a bottom plan view thereof.

The broken line showing of the remaining parts of a portion
of digital audio player is for illustrative purposes only and
forms no part of the claimed design.
